UNITED STATES PATENT OFFICE

LOUIS DAVIS, JR., OF GALVESTON, TEXAS, ASSIGNOR OF ONE-EIGHTH TO DELBERT HULETT AND A. J. STUCKEY, BOTH OF GALVESTON, TEXAS

MACHINE GUN

Application filed May 29, 1931. Serial No. 541,039.

This invention relates to fire arms, and more particularly to a rapid fire gun capable of use for both ground work and on aeroplanes and the like.

One of the primary objects of my invention is the provision of a novel machine gun, which is so constructed that a maximum amount of projectiles can be fired therefrom per minute without danger of the gun jamming or clogging and without danger of the gun overheating.

Another salient object of my invention is the provision of positive means for loading the revolving cylinder of the gun, whereby the cartridges will be fed into the cylinder in a proper step by step movement and into the proper chamber thereof during the timed rotation of said cylinder.

Another important object of my invention is the provision of positive means for ejecting each shell from a chamber of the cylinder at the proper time, whereby all danger of a shell sticking in a chamber of the cylinder after the firing of a cartridge is absolutely precluded.

A further and important object of my invention is the provision of a novel firing mechanism for the cartridges with means for preventing the premature firing of a cartridge.

A further object of my invention is the provision of means whereby the loading, ejecting, and firing mechanism will all operate in a proper sequence relative to one another during the time the rotating cylinder is held stationary and a chamber thereof is in proper alignment with the barrel of the gun.

Another important object of my invention is the provision of novel means automatically operated for locking the cylinder against rotation during the firing, ejecting and loading operation of the cylinder.

A further object of my invention is the provision of novel means for cooling the gun while the same is in operation, said means embodying a water jacket surrounding the barrel of the gun with a positive means for circulating the water through the jacket, said cooling means also embodying a drip arrangement whereby the circulating water can

flow around the rotating cylinder so as to insure the proper cooling thereof and to prevent the distortion thereof under heat.

A further object of my invention is the provision of means whereby all of the operating parts can be actuated from a common operating or master lever, with means for actuating the lever from a prime mover, such as an electric motor, means being also provided for permitting the operation of the gun by hand in case the prime mover should be rendered useless from any cause.

A further object of my invention is the provision of means for automatically swinging the gun both in a horizontal and vertical plane from the prime mover during the firing thereof, whereby the gun can be operated entirely automatically for covering a certain portion of a battle field, means being provided whereby the automatic swinging mechanism for the gun can be disconnected, so that the gun can be sited or trained by hand.

A still further object of my invention is to provide an improved machine gun of the above character, which will be durable and efficient in use, one that will be comparatively simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a side elevation of my improved machine gun, the casing or housing for the operating parts of the gun being shown removed.

Figure 2 is a detail vertical section taken on the line 2—2 of Figure 1 looking in the direction of the arrows illustrating the supporting frame or tripod for the machine gun and the means for operating the actuating parts of the gun from a prime mover.

Figure 3 is a side elevation of the gun showing the opposite side thereof from Figure 1.

Figure 4 is an enlarged fragmentary side elevation of the gun looking from the left hand side thereof and illustrating the ejecting

and firing mechanism, parts of the gun being shown broken away and in section.

Figure 5 is a view similar to Figure 4 showing the position of parts after the gun has been fired and the cartridge shell ejected, the ejecting rod having been returned to its normal position.

Figure 6 is a view similar to Figure 5 showing the position of the ejecting rod prior to the return stroke thereof, parts of the operating lever being shown broken away to illustrate other working parts of the gun.

Figure 6a is a fragmentary detail side elevation of a portion of the ejecting operating mechanism, illustrating the position of these parts prior to the return of the ejecting rod to its normal position.

Figure 7 is an enlarged fragmentary central longitudinal section through the gun illustrating the position of the parts immediately before the firing of the cartridge and illustrating more particularly the main or master operating lever of the gun.

Figure 8 is a transverse sectional view through the gun taken on the line 8—8 of Figure 7 looking in the direction of the arrows and illustrating the mechanism for revolving the cylinder from the main or master operating lever.

Figure 9 is a horizontal section through the gun looking toward the base thereof and illustrating the means of mounting the gun on the base and showing a part of the mechanism for swinging the gun in a horizontal plane during the firing thereof.

Figure 10 is an enlarged fragmentary vertical section illustrating the means for mounting the gun on the base and the main operating means.

Figure 11 is an enlarged fragmentary side elevation of the gun looking from the right hand side thereof, the position of the parts corresponding to Figures 5 and 6, the pitman rod being on its down stroke.

Figure 11a is a view similar to Figure 11 showing parts thereof broken away and in section, to more clearly illustrate the means for feeding the cartridges into the revolving cylinder.

Figure 12 is an enlarged fragmentary side elevation of the gun showing the right hand side thereof and illustrating the position of the parts prior to the firing of the gun and corresponding to Figure 4 of the drawings, the pitman rod being on its up stroke.

Figure 13 is an enlarged fragmentary sectional view with parts broken away and in section, illustrating the position of the loading or cartridge feeding mechanism, the position of the parts corresponding to the position of the parts shown in Figure 8.

Figure 14 is an enlarged fragmentary horizontal section illustrating a portion of the cartridge loading and feeding mechanism

taken substantially on the line 14—14 of Figure 12.

Figure 15 is an enlarged detail perspective view illustrating a part of the cartridge loading and feeding mechanism, and showing more particularly the means for stopping the feeding of the cartridges during the firing of the gun.

Figure 16 is an enlarged fragmentary side elevational view of the cartridge loading and feeding mechanism showing the position of the parts as illustrated in Figures 7 and 11.

Figure 17 is an enlarged fragmentary side elevational view of the cartridge loading and feeding mechanism showing the position of the parts as illustrated in Figures 12 and 12a.

Figure 18 is an enlarged fragmentary detail sectional view illustrating the means for controlling the flow of cartridges from the supply hopper to the feed hopper.

Figure 19 is a horizontal section taken on the line 19—19 of Figure 18 looking in the direction of the arrows illustrating the mechanism for controlling the flow of cartridges from the feed hopper to the feed or guide tracks.

Figure 20 is a vertical section taken on the line 20—20 of Figure 18 illustrating the mechanism for controlling the flow of cartridges from the supply hopper into the feed hopper.

Figure 21 is a view similar to Figure 20 showing the position of the parts after a cartridge has been released from the supply hopper into the feed hopper.

Figure 22 is a view similar to Figure 19 and taken on the line 22—22 of Figure 21 looking in the direction of the arrows.

Figure 23 is an enlarged detail perspective view of the release and holding latch for the operating lever of the cartridge feed mechanism.

Referring to the drawings in detail, wherein similar reference characters designate corresponding parts throughout the several views, the letter A generally indicates my improved gun which comprises a supporting stand B or mount, on which is mounted the gun proper or head C.

The gun proper or head C embodies a novel cartridge supply mechanism D, a cartridge feeding mechanism E, a cartridge firing mechanism F, and the shell ejecting mechanism G.

The gun also embodies a novel locking mechanism H for the rotating cylinder of the gun operating in conjunction with the loading, firing, and ejecting mechanism E, F, and G; and also novel means for swinging the gun proper or head C automatically from the main operating mechanism, forming a part of the gun mount, said swinging mechanism being indicated by the letter I, and a novel cooling mechanism J.

The manner in which the gun proper or

head C is mounted on the base B forms an important part of my invention, but it is to be understood, however, that the gun proper can be mounted in other manners without departing from the spirit or the scope of this invention, and that the gun proper or head C can be mounted in any desired way on an aeroplane or other moving vehicle, to obtain the best advantage therefrom.

As shown the base or mount B comprises a pair of spaced parallel bars 25 to which are secured the rear depending legs 26, and the front forwardly extending leg 27. The front leg 27 can be provided with a foot 28 and the rear legs 26 can be connected together by a cross strap or brace 29. This base or stand can be made in any other desired manner. Adjacent to the front of the base or mount is arranged a pair of transversely aligned trunnions 30, which receive the transverse pivot shafts 31 on which are mounted the depending triangular shaped swinging supporting plates 32, which are arranged in spaced parallel relation. It is to be noted that the pivot shafts 31 extend through the plates 32 intermediate the upper and lower ends thereof, and that the upper ends of the plates have bolted thereto one plate section 34 of a turn table structure 33. The companion turn table plate 35 is rigidly secured in any preferred way to the gun proper or head C. Extending axially through the turn table plates 34 and 35 is the pitman rod 36, which forms a part of the main or master operating mechanism, as will be later described. It is to be noted, however, from the description so far, that the gun proper or head C can be swung in a horizontal path on the turn table plates 34 and 35 using the pitman rod 36 as an axis and also in a vertical plane using the shafts 31 as an axis.

Referring again to the main operating parts of the gun, it is to be noted that the depending plates 32 support a rotatable transversely extending crank shaft 37 to which the pitman rod 36 is connected. This shaft is adapted to be operated mechanically from any suitable prime mover, and I have shown an electric motor 38 for this purpose. This electric motor is bolted directly to one of the depending plates 32 so as to swing therewith and the armature shaft 39 thereof has keyed or otherwise secured thereto a pinion 40 which meshes with a relatively large gear 41 rotatably mounted on a stub shaft 42 carried by one side plate 32. This gear 41 in turn meshes with a smaller gear 43, keyed or otherwise secured to the crank shaft 37. Thus it can be seen that the crank shaft 37 and its pitman 36 can be operated mechanically. Means can also be provided for disconnecting the motor 38 from the crank shaft, so that the crank shaft can be operated by hand in cases of necessity, where the motor is rendered inoperative from any purpose. A hand

crank 44 can be connected to the crank shaft 37 to facilitate the rotation of said crank shaft. The means for swinging the gun proper or head C on the gun mount B will be later described.

The gun proper or head C includes a rigid frame or stock 50, to which is connected the upper turn table or plate 35. This rigid frame has connected therewith and extending forwardly therefrom the gun barrel 51 which can be rifled, if preferred. The forward end of the barrel 51 can also be provided with any preferred type of sight 52. Directly in rear of the barrel 51 is arranged the rotatable cylinder 53 having extending axially therethrough the supporting shaft 54 suitably mounted within the gun frame. This cylinder 53 is provided with an annular row of chambers 55 which are adapted to be brought into successive registration with the barrel 51.

Extending longitudinally of the gun proper C is the master operating lever 56 which is rockably mounted intermediate its ends on a suitable supporting pivot 57 carried by the frame of the head. The forward end of the master operating lever terminates adjacent to the rotatable cylinder 53 and forms means for operating the cylinder as will be later described. The upper end of the pitman rod 36 extends into the frame of the gun proper or head C and is provided with a yoke 58, which receives the adjacent end of the master operating lever 56. A pivot pin 59 connects the yoke with the master operating lever, and thus this lever will be rocked during the reciprocation of the pitman rod 36. Pivotally connected, by means of a pivot pin 60, with the master operating lever 56 forwardly of the pitman rod 36, is an operating lever 61, for rotating the cylinder 53 during the actuation of the gun. This operating lever 61 and the means for operating the cylinder is more clearly illustrated in Figure 8 of the drawings, and it is to be noted that the operating lever 61 is twisted intermediate its ends and that the upper end thereof is bifurcated to provide a pair of spaced fingers 62 and 63. The outer finger 62 constitutes a guide finger and is provided with a laterally extending guide lug 64 for engaging the outer surface of the cylinder 53. The inner finger 63 constitutes an operating finger and is provided with a forwardly directed operating lug 65 which is adapted to engage the inner face of the cylinder 53 and the walls of the chambers 55 to bring about the rotation of the said cylinder. A contractile coil spring 66 is connected with the operating lever 61 at one of its ends and at its other end is connected to the frame 50 of the gun proper or head C. Thus it is to be noted that the guide lug is normally urged into engagement with the outer face of the cylinder and thus normally holds the guide finger

in engagement with the outer surface of the gun and thus the operating finger in proper position relative to the chambers 55. Upon the upstroke of the pitman rod 36 the lever at its forward end will be moved upwardly, which will swing the operating lever 61 upwardly, moving the cylinder 53 a distance equal to the distance between a pair of chambers 55, so that a new chamber will be brought into registration with the barrel 51 and another chamber from out of registration with the barrel. On the down stroke of the pitman rod the forward end of the master lever 56 will be brought downwardly and the operating lever 61 will swing on its pivot 60 allowing the finger 63 to move from out of engagement with the wall of the chamber and thus slide over the rear face of the cylinder into proper position for engagement with the next adjacent chamber.

The feeding mechanism for the cartridges, generally indicated by the reference character E is located on the right hand side of the gun, and the right hand side of the cylinder 53, while the ejecting mechanism for the cartridge shells, generally indicated by the reference character G is located on the left hand side of the gun. As stated, the cartridge feeding mechanism and the cartridge ejecting mechanism operate while the cylinder is held stationary during the firing of a cartridge.

The cartridge feeding mechanism E forms one of the salient parts of my invention, and the cartridges are handled in a novel manner to permit the maximum number of rounds to be fed to the cylinder in the shortest space of time and to properly time the delivery of said cartridges to the proper chambers of the gun. This cartridge feeding mechanism comprises a supply mechanism D, which includes the supply hopper 70 in which the cartridges are initially placed. This supply hopper 70 is held in position above the gun proper by means of a suitable supporting bracket 71, as clearly shown in the drawings. The hopper inclines downwardly and forwardly and terminates in a supply chute or tube 72, which leads into a control hopper 73. The cartridges from the control hopper 73 are fed in proper timed relation to the cartridge feeding mechanism, but it should be understood that the cartridges are simply poured into the supply hopper 70 regardless of their position and that the cartridges are handled in a novel manner by the cartridge feeding mechanism to insure the proper feeding thereof with the projectile end first into the chambers of the cylinder.

The tube or supply chute 72, as stated, extends into the control hopper 73 and has its lower end opened as at 74 and provided with an inclined cartridge guide lip 75. The control hopper 73 is held in place on the gun by a suitable bracket 76 below and forwardly of the supply hopper 70. Means is pro-

vided for preventing the too rapid flow of the cartridges from the tube or supply chute 72 into the control hopper and this means comprises a swinging gate 77 of arcuate form. The gate 77 is hinged at its upper end, as at 78 to one side wall of the control hopper and in its normal position, the gate extends under the open side 74 of the supply chute and in engagement with the lip 75 whereby the cartridges will be prevented from falling into the control hopper. It is to be understood that the opening 74 is of a size as to permit the dropping of one cartridge only at a time therethrough.

In order to further insure the proper dropping of the cartridges one at a time from the supply mechanism D to the feed mechanism E, I provide below the gate 77, a swinging jaw 79, which functions or cooperates with a stationary jaw 80. The jaw 80 is arranged on one side of the control hopper and the swinging jaw 79 is arranged on the other side of the hopper and the jaw 80 extends below the supply tube or chute 72. The jaw 79 is pivoted intermediate its ends, as at 81, in the hopper 73 and its lower end swings toward and away from the stationary jaw 80. The extreme upper end of the jaw 79 above its pivot 81 is provided with an arm 82 which is pivotally connected to a link 83, intermediate the ends thereof. The inner end of the link is pivoted as at 84 to the gate 77 near its pivot. The jaw 79 is actuated by a slide plate 85 mounted for sliding movement in the hopper 73 at one side of the gate and below the pivot point thereof. This slide plate 85 is provided at its rear end with a depending attaching foot 86, which is riveted or otherwise secured to a slide track 87, which is mounted directly below the jaws 79 and 80. This slide track 87 is provided with a longitudinal slot 88 which is enlarged intermediate its ends, as at 89. The slide plate 85 is provided with an inclined surface forming a cam trip 90, and it is obvious that as the slide and the slide track is reciprocated back and forth, by means, which will be later described, that the cam surface 90 will strike the jaw 79 and swing the same on its pivot and hold the same in a closed position. A contractile coil spring 91 is connected to the upper end of the link 83 and to a rigid portion of the control hopper and this spring functions to normally hold the jaw in an open position as shown in Figure 21. As the jaw 79 is swung to an open position and to a closed position the gate 77 is actuated therewith and by referring to Figure 20, it can be seen that when the jaw 79 is in an open position the gate 77 is in its closed position. Thus when a cartridge is being fed to the slide track 87, further delivery of cartridges between the jaws is prevented. As shown in Figure 21, when the jaw 79 is in its closed position the gate 77 will be in its open position.

tion, so that a cartridge can be delivered from the chute into and between the jaws.

When the jaws are opened a bullet will be allowed to drop onto the slide track 87 and the weighted end thereof will swing through the slot 88, and the bullet or cartridge will be suspended from the slide track by means of its base. The slide track 87 and the plate 85 is reciprocated back and forth in proper timed relation in a novel manner from the main operating mechanism as will be later described, but it is to be noted that at the present time, that the forward end of the slide track 87 carries a hook 92, the forward end of which is provided with a curved face 92' for cooperation with certain other parts, as will be later set forth, as stated above. A contractile coil spring 93 is connected with the rear end of the slide track 87 and to the frame of the gun head and normally holds the slide plate in a rearward position with the narrow portion of the slot lowermost, so that the parts will normally assume a position shown in Figures 19 and 20. When the slide plate is moved forwardly against the tension of the spring 93, the widest portion 90 of the slot 88 will be brought below the control hopper, which will permit the base of the cartridge to fall through the slot, so that the cartridge can be delivered to the cartridge feed mechanism E, which will now be described in detail.

The cartridge feeding mechanism E embodies a pair of spaced guide tracks 95, which are rigidly secured to the frame of the gun head and these tracks extends under the control hopper in proper spaced relation thereto and rearwardly thereof, as clearly shown in Figures 11a and 13. The tracks 95 are spaced a sufficient distance apart to allow the weighted end of the cartridge to fall between the same but to hold the base end thereof, so that the cartridge will be held in a suspended position as shown in Figures 11a and 13. The extreme rear ends of the tracks 95 are cut out or spaced a further distance apart as indicated by the reference character 96 so that when the cartridges reach the enlarged portion of the track the same will be released from the track and fall therefrom.

The cartridges are gradually worked to the rear portion of the track 95 by means of a feed finger 97, which depends from a slide plate 98 mounted for reciprocating movement on a stationary guide rod 99 carried by the gun frame. This guide rod 99 and the slide plate 98 is mounted at one side of the control hopper 75 and the feed finger 97 extends between the guide tracks 95 as shown. The feed finger 97 acts in conjunction with the slide track 87 and the plate 85 and in fact the slide track is actuated from the slide plate 98. Pivottally connected with the slide plate 98 and projecting forwardly therefrom is an operating hook 102, which is actuated

by means which will be later set forth. This hook 102 is provided with a right angularly disposed upstanding arm 100 for engaging the hook 92.

It is to be noted however, that the slide plate and the finger 97 is reciprocated back and forth and that when a bullet or cartridge falls into the control hopper between the tracks, that upon rearward movement of the finger the same will engage the cartridge and move the same back on the track 95 and that upon the return movement of the slide plate the finger 97 will be moved forwardly of the hopper to allow the dropping of another bullet or cartridge between the tracks. This movement is continued until the cartridges are gradually fed rearward on the tracks so that a cartridge will be fed one at a time to the enlarged portion 96 of the tracks, where a cartridge will fall to certain other operating mechanism. When the finger 97 is in its extreme forward position, it is obvious that the arm 100 will engage the hook 92 and move the slide plate 85 and the slide track 87 forwardly, which will move the jaw 79 to its closed position as shown in Figure 21 and the enlarged portion 89 of the slide track 87 below the control hopper, whereby the bullet will be dropped.

A stop finger 105 is swung back and forth in front of the enlarged portion 96 of the cartridge guide tracks 95, by a novel operating mechanism, which will now be described. It is to be noted that this stop finger depends from a lever 106 mounted above and at one side of the said cartridge guide tracks 95 and this lever is rockably mounted intermediate its ends as at 107 on the forward end of a bar 108, which carries a guide 109 received on the stationary guide rod 99. The forward end of the lever 106 is pivotally connected as at 110 to the upstanding ear 111 formed on an operating lever 112, which extends forwardly toward the front of the gun. This operating lever 112 terminates in a hook 113, for a purpose, which will be later described. This lever 112, intermediate its ends and rearward of the pivot 107 for the swinging lever 106, is pivotally connected as at 114 to the plate 108. The rear end of the operating lever 112 terminates in a nose 115 and has formed thereon an upstanding arm 116. This arm has connected thereto a contractile coil spring 117, the opposite end of which is connected to the plate 108. This spring normally functions to hold the nose end of the operating lever 112 in a raised position.

Pivottally connected to the plate 108 and extending rearwardly therefrom is the operating bar 118, the lower face of which can be provided with one or more teeth 119. These teeth are engaged by the laterally extending dog 120 formed on the upper end of a swinging lever 121, which lever is rockably mounted intermediate its ends on a pivot 122 car-

ried by the frame, of the gun head. The lever 121 is operated by a link 123, which is pivotally connected to the lower end of the lever by means of a pivot pin 124. This link 123 extends forwardly and has its forward end angled upwardly and pivotally connected as at 125 to the three arm lever 126. The lever 126 is rockably mounted on a frame carried pivot pin 127, approximately at the point of connection of the three arms thereof. These arms are indicated respectively by the numerals 128, 129, and 130. The arms 128 and 129 are in longitudinal alignment, while the arm 130 extends forwardly and at right angles thereto and is pivotally connected as at 131 to the extreme forward end of the master operating lever 56. Thus upon movement of the master operating lever 56 the three arm lever 126 will be swung on its pivot 127 causing the swinging of the swinging lever 121 through the medium of the link 123. The dog 120 formed on the swinging lever 121 also actuates an operating rod 132 (see Figure 11a of the drawings) the dog 120 engaging a notch 133 formed in said operating rod. It is to be noted at this point that the rear end of the operating rod 132 is mounted for swinging movement on a swinging link 134, and that the rear end of the bar has connected thereto a contractile coil spring 135, the lower end of which is rigidly connected to a swinging dog 136, the forward end of which is urged into engagement with a ratchet wheel 137, which forms a part of the gun head swinging mechanism, as will be later set forth (see Figure 1 of the drawings). The rear end of the slide bar 118 is supported for swinging movement by means of a link 138 mounted on a suitable pivot 139 carried by a part of the gun frame or head.

Referring again to the operation of the stop finger 105, it is to be noted that the plate 108 (see Figures 15, 16 and 17) carries a pivoted detent 140 having a depending finger 141 arranged in the path of a stop 142 carried by the frame of the gun. The upper edge of the detent 140 is provided with a laterally extending latch finger 143, which normally engages over the nose 115 of the swinging lever 112, which prevents the swinging of this lever and the consequent raising of the stop finger 105. This detent is normally held in a lowered position by means of a contractile coil spring 144, which is connected with said detent and with a frame part of the gun.

Referring again to the operating mechanism for the swinging finger and the other cooperating parts, it is to be noted that the frame of the gun, adjacent to the forward part thereof (see Figures 11 and 11a) has rockably mounted thereon a throw lever 147. This lever is mounted intermediate its ends to a pivot pin 148 and has the lower end thereof operatively connected to the arm 129 of

the three arm lever 126 by means of a link 149. Thus upon movement of the three arm lever 126 from the master operating lever 56, the throw lever 147 will be actuated back and forth. The extreme upper end thereof is provided with a catch lug 150, which is arranged in the path of the hooks 102 and 113.

When the cartridges have been fed backward against the stop finger 105, the swinging lever 121 will be swung on its pivot through the medium of the operating link 123, which will move the rack bar 118 rearward and the depending finger 141 of the detent 140 against the stop 142 raising the latch lug 143 above the nose 115 of the lever 112. This will allow the swinging of the lever 112 on its pivot 114 under the influence of its spring 117. The swinging of the lever 112 will move the nose end thereof 113 in the path of the lateral lug or finger 150 formed on the lever 148. Simultaneous with this movement the finger 105 will be lifted due to its connection with the link 106 as clearly shown in Figures 16 and 17. The cartridges can now be moved back by the feed finger 97 until a cartridge rides in the enlarged portion of the guide track 95, where the same is allowed to drop. The movement of the cartridges through the enlarged portion 96 of the track 95 is facilitated and insured by means of a swinging tap plate 151, mounted on the track 95 directly above the enlarged portion thereof. It can be seen that the swinging tap plate 151 is provided with an ear 152 the upper end of which has pivotally connected thereto the forward end of the rod 132 which is actuated from the swinging lever 121, as heretofore brought out. Thus simultaneously with the backward movement of the bar 118 and the raising of the stop finger 105 the tap plate 151 will be raised, but that upon initial start forward of the plate 132 the tap plate will move downward forcing the cartridge 110 through the enlarged portion of the track.

The finger 150 on the lever 147 will catch the nose 113 and return the parts to their normal position for further actuation.

At this point, it is to be also noted that the lateral finger 150 will engage the hook 102 which functions to actuate the feed finger 97 and the flow of cartridges from the control hopper 73, as previously described.

Mounted on the gun head forwardly of the hook 92 is an inclined stop plate or shoe 325. This shoe 325 is arranged in the path of the hook 92 and consequently when the slide plate 85 has been brought forwardly the hook 92 will be raised by said plate 325 allowing the quick release of the slide plate and associated parts from hook 102, so as to allow the rearward movement of the plate 85 under influence of its spring 93 and operating mechanism. A resilient dog 326 is connect-

- ed with track slide 98 and the hooked end of this dog 326 normally engages the upright 100 of the hook 102 for holding the same in a raised position. However, when the track 5 slide 98 moves rearwardly this dog 326 is moved from out of engagement with the hook 102, by the contacting of the dog 326 with the hopper 23, allowing the hook 102 to again drop in the path of the operating lever 147.
- 10   Mounted below the track 95 directly at the enlarged portion 96 thereof is a cartridge guide box structure 153, through which the cartridges fall. A cartridge delivery tube is arranged in a horizontal position directly 15 in rear of the cylinder 53 and is in alignment with a chamber 54 of the cylinder at the time the cylinder is held stationary during the loading, firing, and shell ejecting operation. The guide box structure 153 opens 20 into the tube 157. The cartridge then falls from the tracks 95 into the box 153 on a reciprocating feed control finger 165. This finger 165 moves back and forth above the entrance slot 166 of the cartridge feed tube 157. The rear-end of this slide finger 165 is pivotally connected as at 167 to the swinging operating lever 168, mounted at its lower end as at 169 on the frame of the gun. A laterally extending arm 170 which is formed 25 on the upper end of the lever 168 can have pivotally connected thereto an operating link 171 which extends forwardly and is pivotally connected as at 172 to a main operating rod 173, which is pivoted as at 174 to the three arm lever 126. Thus it is to be noted that with the swinging of the three arm lever 126 the slide finger 165 is operated and that the same operates in conjunction with the cartridge turning mechanism, feed mechanism 30 and the like. In order to guide the rod 173 in swinging movement an arm 161 is rockably mounted as at 162 on the frame of the gun head and is connected as at 164 to the rear end of the rod 173.
- 35   A plunger 178 is reciprocately mounted in the cartridge feed chute 157 and is moved back and forth so as to slide the cartridge in the chute in proper timed relation into a chamber 54 of the cylinder 53 at the time the cylinder is held stationary. This plunger 175 is provided with a depending bracket 176 to which is pivotally connected a link 177 which extends forwardly therefrom and which is in turn pivotally connected as at 178 to the upper end of a swinging lever 179. This swinging lever 179 is rockably mounted on a frame carried pivot 180. Directly above the pivot 180 the lever 179 has pivotally connected thereto an operating link 181. This link 181 is in turn pivotally connected to the extreme lower end of the three arm lever 126, as indicated by the reference character 182. It is therefore to be noted that the 40 plunger rod 175 also functions in direct ac-
- 45   cordance with the other part of the cartridge feed mechanism.
- 50   As the cartridges are fed into the chambers of the cylinder 53, the cylinder is rotated in a step by step motion previously 70 described so as to bring a loaded chamber in registration with the barrel 51 of the gun, where the cartridge is fired by the novel firing mechanism F, which will now be described.
- 55   The firing mechanism F comprises the reciprocating firing pin 185 mounted in suitable guides 186 forming a part of the gun directly in rear of the rotating cylinder 53. This firing pin is normally held rearward of 80 the cylinder 53 by means of a light expansion coil spring 187 which engages one of the guides 186 at one end and a collar 188 on the firing pin at its opposite end. The firing pin extends beyond the rearmost bracket 186 and in the path of the firing hammer 190 which is in the nature of an elongated reciprocating rod. This hammer 190 is mounted in suitable guides carried by the frame of the gun and is provided with a cross pin 191 which is 85 engaged by the upper yoke end 192 of the firing lever 193. This firing lever 193 is rockably mounted adjacent to its lower end on a suitable pivot pin 194 and the extreme lower end of the firing lever is engaged by a 90 heavy contractile coil spring 195. This coil spring 195 functions to urge the hammer into engagement with the firing pin for forcibly moving the same into contact with the cartridge which is to be fired. The extreme rear 100 end of the hammer is provided with a right angled arm 196 which is normally engaged and held by the nose end 197 of the trigger 198. This trigger 198 is rockably mounted as at 199 intermediate its ends on a swinging 105 reset lever 200. The nose end of the trigger is held down toward and in engagement with the angled arm 196 of the hammer by means of a light contractile coil spring 201. The reset lever 200 is rockably mounted intermediate its ends as at 202 on a part of the frame of the gun head and the extreme lower end of the lever has pivotally connected thereto, as at 203 the forwardly extending operating link 204. This link at its forward 110 end is pivoted as at 205 to the depending rock lever 206, which is suspended for swinging movement at its upper end from the frame of the gun. The extreme lower end of the lever has pivotally connected thereto the main operating link 173 previously mentioned in connection with the cartridge feeding mechanism. It is to be noted that this main operating link 173 is actuated from the three armed lever 126 and thus through the operating of the three armed lever the reset lever 200 will be rocked back and forth so as to carry the trigger therewith, for a purpose, which will be more clearly set forth.
- 115   Novel means is provided for swinging the 120 plunger rod 175 also functions in direct ac-
- 125
- 130

Novel means is provided for swinging the 130

trigger on its pivot 199 so as to move the nose end thereof from out of engagement with the lateral arm 196 of the hammer, so that the hammer can be brought forcibly forward into engagement with the firing pin under the influence of the heavy contractile coil spring 195. This release mechanism for the trigger also operates in conjunction with the reset lever 200 and the trigger release includes a swinging trip arm 207 having formed on its upper end the laterally extending lip 208, which is arranged in the path of the upper end of the trigger in rear of its pivot 199. This trip arm 207 is pivoted at its lower end, 15 as at 207' on the rear end of a double armed lever 209, which is rockably mounted intermediate its ends on a pivot 210 carried by a part of the frame. The forward end of the lever 209 has pivotally connected thereto as 20 at 211 an upright bar 212, having formed thereon or secured thereto the laterally extending lug 215'. The upper end of the upstanding bar 212 is normally urged forwardly by means of a contractile coil spring 213. 25 The forward edge of the upright bar 212 adjacent to its lower end is provided with a notch 214 into which is received at certain times a cross pin 215 carried by the rear end of the master operating lever 56. It is thus 30 obvious that upon initial upward movement of the master operating lever at its rear end that the pin 215 riding in the notch 214 will lift the upright rod 212 and swing the rear end of the double ended lever 209 down, 35 which in turn will pull down on the trip arm 207 allowing the release of the trigger 198, whereby the nose end 197 thereof will ride upward and out of engagement with the lateral arm 196 on the hammer 190. The laterally extending lug 113 carried by the up-right bar is normally fitted in a notch 215' formed in the nose end 217 of a swinging lever 218 forming a part of a quick release mechanism now to be described. The rear 40 end of the release arm 218 is pivotally mounted on a supporting arm 219 rigidly connected with a rock lever 220 pivotally secured intermediate its ends, as at 221 on a part of the frame of the gun. The forward end of this lever 220 is yoked or bifurcated, as at 222 for receiving the pin 215. The release lever 218 slides through a guide 223 carried by the frame of the gun and is normally urged downward toward the lug 215' and toward 45 the lever 220 by means of a contractile coil spring 224.

Immediately after the firing of the gun the trigger starts to move forwardly under the swinging movement of the reset lever 200 and synchronous with this movement the rear end of the master lever starts to raise which swings the lever 220 on its pivot, which movement is transmitted to the nose end of the top lever 218 and the notch 216 swings out from the lug 215' of the upright bar 212. This allows the upright bar to swing so that the notch 214 will ride off of the cross pin 215 of the master operating lever, and allows the upright arm to immediately move downward and swing the two armed lever 209 on its pivot, raising the release latch or trip 207 above the trigger. The trigger continues to move forwardly with the swinging reset lever 200 and the nose end of the trigger snaps over the lateral arm 196 of the hammer 190. Upon the downward rear end stroke of the master lever 56 the reset lever 220 is swung rearwardly carrying the trigger 198 therewith and also the hammer 190, resetting these parts and the cross pin 215 of the master lever 56 is moved downward swinging the bottom lever 220 of the release mechanism downward and moving the nose end 217 of the upper lever 218 forwardly and over the lug 215' of the upright bar 212 resetting and locking the parts. The gun is then again ready to be fired.

Operating in timed conjunction with the firing mechanism is the cartridge shell ejecting mechanism G, which will now be described.

The cartridge shell ejecting mechanism G comprises a shell ejecting rod 230 mounted for reciprocatory movement in suitable guides on the gun frame. The forward end of the shell ejecting rod can be tapered as at 231 to facilitate the entrance of the same into a chamber of the cylinder and into the shell to eject the same. This ejecting rod 230 is reciprocated back and forth in its proper timed relation from the master operating lever 56 and the operating mechanism therefore is of a novel construction. The same embodies a swinging operating lever 232, which lever is rockably mounted adjacent to its lower end on a suitable pivot pin 233 carried by the gun frame. The extreme upper end of the lever is connected to the forward end of the shell ejecting rod 230 by means of a pin and slot connection 234. Pivotally connected to the lever 232 above the pivot point 233 thereof, as at 235, is a rearwardly extending operating link 236 having a hook 237 formed on its rear end. Pivotally connected to the extreme lower end of the operating lever 232 below its pivot 233 is a second operating or return link 238, the rear end of which is provided with a hook 239. These hooks are adapted to engage at certain proper times a laterally extending lug 240, carried by the reciprocating bar 241 which extends longitudinally of the gun frame. The reciprocating bar 241 is guided in its movement by a suitable guide carried by the gun frame and the extreme rear end of the reciprocating bar 241 is pivotally connected as at 242 to the outer end of one arm of a bell crank 243. This bell crank 243 is rockably mounted at its angle as at 244 on a part of the gun frame and the outer end of the other arm thereof is

provided with a slot 245, which receives the cross pin 215 carried by the rear end of the master operating lever 56. By this construction, it can be seen that as the rear end of the master operating lever 56 raises and lowers that the bell crank 243 will be rocked which will transmit a reciprocatory movement to the reciprocating bar 241.

Means is provided for lifting the upper

6 hook link 236 above and out of engagement with the lateral lug 240 of the reciprocating bar 241 at the proper time for preventing further inward movement of the ejecting rod 230 and this means includes a swinging lever 246 rockably mounted on the gun frame as at 247 forwardly of the cylinder 53. The outer end of this swinging lever 246 has connected thereto a depending link 248 which in turn is pivotally connected to an arm 249

10 formed on the upper end of the upper hook link 236. The swinging lever 246 is raised and lowered by means of a depending link 250 which is pivoted at its upper end as at 251 to the swinging lever 246 intermediate the ends thereof. The lower end of the link 250 is pivotally connected as at 252 to the forward end of a double armed lever 253, which double armed lever is rockably mounted at a point intermediate its ends as at 254 to the frame of the gun. The rear end of the lever 253 is pivotally connected to an operating link 255, the upper end of which is pivoted as at 256 to a swinging operating lever 257. This lever 257 is rockably mounted 15 at its rear end on a pivot pin 258 to the frame of the gun in rear of and below the rotating cylinder 53. The forward end of the swinging lever 257 is pivotally connected as at 259 to the front of the master operating lever 56.

40 The shell operating means operates as follows: Considering that a cartridge has been fired and the cylinder 53 has been rotated bringing a chamber filled with a fresh cartridge into registration with the barrel 51 and moving the firing cartridge or shell to the left in registration with the ejector rod 230, the reciprocating rod 241 will be drawn rearward by the master operating lever 56 and at this time, the hooked end 237 of the 45 upper hooked link 236 will be in engagement with the lateral lug 240, which will draw the upper hooked link 236 rearwardly swinging the lever 232 on its pivot. This will force the ejector rod 230 rearwardly and into 50 the chamber of the cylinder 53 carrying the exploded shell and forcing the shell from out of the chamber. When the ejector rod 230 has moved to its extreme forward position, the front end of the master lever 56 55 will have been moved a sufficient distance downward to rock the lever 237, which movement will be transmitted to the double ended lever 253 moving the rear end thereof downward and the forward end thereof upward. 60 The upward movement of the front end of

the double lever 253 will be transmitted to the link 250, which will raise the swinging lever 246. The upward raising movement of the swinging lever 246 will lift the top swinging link 236 so that the hooked end thereof 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500

Acting in conjunction with the rotating cylinder 53 for holding this cylinder positively against rotation during the firing, loading, and ejecting operation, I provide the novel locking mechanism H, which will now be described: The cylinder locking mechanism H, embodies a reciprocating lock pin 260, slidably mounted in the frame of the gun in rear of the cylinder 53. This lock pin 260 is movable into and out of the lowermost chamber of the cylinder in proper timed relation and it is obvious that when the pin is in one of the chambers of the cylinder, that the cylinder will be positively held against rotation. The rear end of the reciprocating lock pin 260 is provided with a guide eye 261, which is slidably mounted on a stationary guide rod 262, which forms a part of the frame of the gun. Operating in conjunction with the guide eye 261 is a latch link 263 having a latch head 264 formed on the rear end thereof for engaging over the eye 261. This latch link or lever 263 is pivotally connected at its forward end, as at 264 on the upper end of an arm 265 carried by the rocking lever 257 which, as previously described is connected to the forward end of the master lever 56. A contractile coil spring 266 engages the latch lever 263 and normally urges this lever downwardly and the latch end thereof toward the eye 261. A combined stop and guide bar 267 limits the downward swinging movement 130

of this latch lever under the influence of its spring.

The operation of this part is as follows: During the downward swinging movement of the lever 257, its arm 265 is drawn rearwardly carrying the latch lever 263 therewith, which moves the nose end thereof 264 in rear of the guide eye 261. The spring 266 tends to draw the latch 263 down in front of the guide eye 16 and as the rounded end of the nose 264 rides in rear of the guide eye, the same moves the guide eye 261 slightly rearward, causing the initial starting of the backward unlocking movement of the cylinder locking pin 260 15 against the tension of a coil spring 270 disposed about the said pin. It is to be noted that the spring 270 engages at its rear end against a part of the frame of the gun and at its forward end against the collar 271 rigidly 20 secured to the said pin. As the lever 257 swings upwardly its arm 265 will be pushed rearwardly causing the nose end to push the eye 261 rearward and the pin from out of engagement with the cylinder. At this time the 25 cylinder rotating means, previously described, will function. As the latch lever 263 rides forwardly, the inclined lower face thereof 272 will ride on the top face of a guide pin 273 carried by the guide 267, which will raise the 30 latch lever up and position the nose 264 above the guide eye 261, allowing the return of the pin to its normal locking position under the influence of its spring 270.

It is to be noted that certain parts of the 35 device are spring pressed and that certain parts are normally returned to their normal positions by means of coil springs. In this regard, it is to be noted that both the link 250 and the link 248 of the swinging lever 40 246 have connected thereto coil springs 274 and 275 respectively, which normally urge the latch lever 236 to its normal position for engagement with the lug 240 on the reciprocating bar 241.

45 From the foregoing description, it can be seen that the loading mechanism E, the firing mechanism F, the ejecting mechanism G and the locking mechanism H all function together in proper relation to bring about the 50 desired result.

As stated in the forward part of the description, I have provided means I for swinging the gun head in a portion of a revolution, so that the gun will automatically control a 55 certain portion of a battle field. The gun head swinging mechanism I includes the ratchet wheel 137 heretofore mentioned and the spring pressed dog 136. It is to be noted that the opposite faces of the ratchet wheel 60 137 has secured thereto for rotation therewith side discs 280, which discs extend beyond the periphery of the ratchet wheel and form guides for the operating ratchet dog 281, which works opposite to the dog 136. The 65 dog 136 acts merely in the nature of a lock to

prevent retrograde movement of the ratchet wheel.

The operating ratchet dog 281 extends forwardly and is pivotally connected as at 282 to the three arm lever 126 above the pivot point 127. Thus during the rocking of the three arm lever 126 by the master lever 56 the ratchet dog 281 will be operated back and forth and the teeth of the ratchet wheel 137 advancing the ratchet wheel in a step by step movement. The dog 281 is normally held in a lowered position toward the ratchet wheel by means of a contractile coil spring 283. The outer side plate or disc 280 is connected with the ratchet wheel 137 and is provided with a crank pin 284, which is received in a notch 285 in an operating pitman rod 286. The forward end of this pitman rod is eccentrically connected, as at 287 with the top turn-table plate 35. Thus as the pitman rod is reciprocated back and forth, the gun head will be turned or oscillated in an arc of a circle. As shown, the connection of the pitman rod 286 with the top plate 35 is by means of a hinge joint and the pitman rod extends rearwardly of the gun and terminates in a handle 288. Thus when it is desired to sight the gun, the handle 288 is merely grasped so as to swing the pitman above the crank pin 284 and out of engagement therewith.

I have also provided means for swinging the gun on its horizontal pivot 31 and this means may be of any preferred character, but as shown, embodies a bell crank lever 290 pivoted at its angle, as at 291 on the lower frame or gun mount B. The lower arm of the bell crank 290 has pivotally connected thereto the forwardly extending link 292, the forward end of which is connected as at 293 with the lower ends of the side plate 32 of the gun mount. It is obvious that when the bell crank 290 is rocked, that the link 292 is drawn forwardly or rearwardly, which will rock the gun on the pivot 31. Any desired means can be employed for rocking the bell crank 290 and as shown I have provided a hand lever 294 rockably mounted on a segmental rack 295. The forward end of the lever beyond its pivot has connected thereto a link 296, which is connected to the outer end of the upper arm of the bell crank 290. The hand lever 294 can be locked in any preferred adjusted position by means of a dog 297 carried by the hand lever for selective engagement with any tooth of the segmental rack.

I can also provide means for locking the gun against action and this means may comprise a reciprocating rack bar 300, slidably carried by the gun mount B. The rear end of the rack bar 300 is angled upwardly and rearwardly as at 301 and has a pin and slot connection 302 with an upright hand lever 303, which hand lever is rockably mounted

intermediate its ends on a supporting bracket 304. By this arrangement the rack bar can be swung into and out of engagement with the main operating gear 41 for the gun, which

5 will hold this gear against rotation. It is to be understood that any desired means may be employed for locking the hand lever against movement.

Due to the fact that the gun operates very rapidly, it is necessary to provide an efficient means for cooling the same. This cooling means indicated by the reference character J, as heretofore stated, comprises a water jacket 305, which preferably surrounds the 15 major length of the barrel 51. This water jacket is provided with a rearwardly extending chamber 306, which overlies the upper portion of the cylinder 53 directly above the firing chamber of the cylinder. As shown, a 20 guide block 307 is provided for the cylinder and is of substantially an arcuate form in cross section and this guide block, directly above the cylinder 53 is provided with drip openings 308 which register with drip openings 25 309 formed in the chamber 306. It thus can be seen that the water from the chamber 306 is allowed to drip down over the cylinder 53, thereby efficiently cooling the same. In view of the fact that the cylinder is provided 30 with a number of chambers 55 and that one chamber is fired at a time, the cylinder 53 will have an ample time to be efficiently cooled irrespective of the rapid discharge of the cartridges. The water dripping over the cylinder 35 53 is caught in a drip pan 310 carried by the swinging head of the gun and this pan has connection with the water supply tank 311 through the medium of a flexible water return hose 312. This tank is preferably secured to a face plate 313, which can be bolted or otherwise secured to one of the side 40 triangular plates 32 of the gun frame. This face plate 313 also has mounted thereon a water pump 314, which has been shown to be of a cylinder and piston type. It is to be understood that any desired type of pump may be used, in lieu of the one shown. The 45 piston rod 315 of the pump is connected by means of a crank 316 with the main crank shaft 37, as clearly shown in Figures 2 and 3 of the drawings. The outlet of the pump has connected therewith a flexible water supply hose 317, which leads to the water jacket 305, as shown. The intake side of the pump 50 314 is connected by means of a pipe 318 with the lower end of the supply tank 311.

Changes in details may be made without departing from the spirit or the scope of this invention, but what I claim as new is:

60 1. A machine gun comprising a barrel, a cylinder rotatably mounted in rear of the barrel, having a plurality of chambers therein, means for rotating the cylinder for successively bringing the chambers therein in registration with the barrel, means for auto-

65 matically firing a cartridge in the chamber which is in registration with the barrel, means arranged on one side of the cylinder for automatically feeding cartridges successively into the chambers of the cylinder, 70 means arranged on the other side of the cylinder of the gun for automatically ejecting exploded shells from the cylinder, an elevated hopper for supplying cartridges to the feeding mechanism, means under said hopper 75 for supporting a series of cartridges in end-wise relation and means for delivering a cartridge one at a time to the feed mechanism.

2. A gun comprising a gun mount, a gun head mounted on the mount for swinging movement in a horizontal plane, the gun head including cartridge firing, feeding and shell ejecting mechanism, a motor for operating said mechanism, and means for automatically oscillating the gun head in a horizontal path including, driving ratchet means a pitman rod for operating said driving ratchet, said pitman rod releasably engaging said driving ratchet and a crank connected with the gun head. 80 85 90

3. A machine gun comprising a gun mount, a base rockable on the mount in a vertical plane, a gun head mounted on the base for movement in a horizontal plane, means for automatically swinging the gun head in a horizontal plane on the base, and manual means for rocking the base including a hand lever, a bell-crank connected therewith, and a link extending from the bell-crank to the lower end of the base. 95 100

4. A machine gun comprising a gun mount, a crank shaft rotatably mounted on the gun mount, means for rotating the crank shaft, a pitman rod connected with the crank shaft, a gun head, a turn-table structure including a pair of facing plates secured respectively to the gun head and the gun mount, the pitman rod extending through the plate, a master operating lever rockably mounted intermediate its ends in said gun head and having operative connection with the pitman rod, said gun head including a barrel, a cylinder rotatably mounted in rear of the barrel having a plurality of chambers therein, means actuated from the master lever for turning the cylinder in a step by step movement for successively bringing the chambers in registration with the barrel, means for firing a cartridge in the chamber which is in registration with the barrel from the master operating lever, means for feeding cartridges to a chamber of the barrel from said master operating lever, and means for ejecting exploded shells from the cylinder actuated from said master operating lever. 105 110 115 120

5. In a machine gun, a barrel, a cylinder rotatably mounted in rear of the barrel having a plurality of chambers therein, means for rotating the cylinder in a step by step movement for successively bringing the chambers 130 125

into registration with the barrel, and means for feeding cartridges to the chambers including an enlarged elevated cartridge supply hopper, and a control hopper for delivering cartridges one at a time in proper position to the feed mechanism.

6. In a machine gun, a barrel, a cylinder rotatably mounted in rear of the barrel having a plurality of chambers therein, means for rotating the cylinder in a step by step movement for successively bringing the chambers into registration with the barrel, means for feeding cartridges to the chambers including an elevated cartridge supply hopper, and a control hopper for delivering cartridges one at a time to the feed mechanism, said means including a tube extending into the control hopper from the supply hopper having an open bottom, a gate movable toward and away from said open bottom, a pair of delivery jaws arranged below the gate, one of said jaws being stationary and the other being movable, means operatively connecting the movable jaw with the gate, whereby upon movement of the gate to a closed position, the movable jaw will be swung to an open position, and means for positively actuating the movable jaw.

7. In a machine gun, a barrel, a cylinder rotatably mounted in rear of the barrel having a plurality of chambers therein, means for rotating the cylinder in a step by step movement for successively bringing the chambers into registration with the barrel, means for feeding cartridges to the chambers including an elevated cartridge supply hopper, a control hopper for delivering cartridges one at a time to the feed mechanism, said means including a tube extending into the control hopper from the supply hopper having an open bottom, a gate movable toward and away from said open bottom, a pair of delivery jaws arranged below the gate, one of said jaws being stationary and the other being movable, means operatively connecting the movable jaw with the gate, whereby upon movement of the gate to a closed position, the movable jaw will be swung to an open position, means for positively actuating the movable jaw, said means including a slide plate reciprocatively mounted in the control hopper having a cam surface thereon for engaging the outer face of the movable jaw.

55 8. In a machine gun, a barrel, a cylinder rotatably mounted in rear of the barrel having a plurality of chambers therein, means for rotating the cylinder in a step by step movement for successively bringing the chambers into registration with the barrel, means for feeding cartridges to the chambers, and means for delivering cartridges one at a time to the feed mechanism including a cartridge supply hopper, a control hopper arranged below and directly above the feed

mechanism, a delivery tube extending to the supply hopper into the control hopper having the lower end thereof open, a gate pivoted at its upper end movable toward and away from the open end of the delivery tube having a pivoted arm secured thereto at one side of its pivot, a pair of jaws arranged in the control hopper directly below the open end of the delivery tube and above the feed mechanism, one of said jaws being rigidly mounted and the other jaw being rockably mounted intermediate its ends and movable toward and away from the rigid jaw, an arm rigidly connected to the upper end of the movable jaw beyond its pivot, pivotally connected to the arm of the gate, spring means engaging the pivoted arm normally moving the gate away from the delivery tube, and means for positively operating the gate including a slide plate arranged in the control hopper having a cam surface for engaging the gate adjacent to the lower end thereof.

9. In a machine gun, a barrel, a cylinder rotatably mounted in rear of the barrel having a plurality of chambers therein, means for rotating the cylinder in a step by step movement for successively bringing the chambers into registration with the barrel, means for feeding cartridges to the chambers, means for delivering cartridges one at a time to the feed mechanism including a cartridge supply hopper, a control hopper arranged below and directly above the feed mechanism, a delivery tube extending to the supply hopper into the control hopper having the lower end thereof open, a gate pivoted at its upper end movable toward and away from the open end of the delivery tube having a pivoted arm secured thereto at one side of its pivot, a pair of jaws arranged in the control hopper directly below the open end of the delivery tube and above the feed mechanism, one of said jaws being rigidly mounted and the other jaw being rockably mounted intermediate its ends and movable toward and away from the rigid jaw, an arm rigidly connected to the upper end of the movable jaw beyond its pivot, pivotally connected to the arm of the gate, spring means engaging the pivoted arm normally moving the gate away from the delivery tube, means for positively operating the gate including a slide plate arranged in the control hopper having a cam surface for engaging the gate adjacent to the lower end thereof, and a slide track movable through the control hopper below the gate connected with the slide plate having a longitudinal slot for permitting the weighted end of the cartridges to fall therethrough, a portion of said slot being enlarged to permit the entire cartridge to fall therethrough, and means for reciprocating the slide track.

10. A machine gun comprising a barrel, a cylinder rotatable in rear of the barrel, hav-

- ing a plurality of chambers therein, means for rotating the cylinder in a step by step movement for successively bringing the chambers thereof into registration with the barrel, means for feeding the cartridges one at a time to the chambers of the gun including a pair of guide tracks for receiving cartridges therebetween, the guide tracks being enlarged to permit a cartridge to fall therethrough adjacent to their rear end, means for supplying a cartridge at a time to the guide tracks, means for moving the cartridges rearward on the guide tracks one at a time to the enlarged portion of the track, a cartridge delivery chute arranged in rear of the cylinder for position in registration with one of the chambers thereof when the cylinder is stationary for receiving a cartridge dropped from the guide tracks.
- 20 11. A machine gun comprising a barrel, a cylinder rotatable in rear of the barrel, having a plurality of chambers therein, means for rotating the cylinder in a step by step movement for successively bringing the chambers thereof into registration with the barrel, means for feeding the cartridges one at a time to the chambers of the gun including a pair of guide tracks for receiving cartridges therebetween, the guide tracks being enlarged to permit a cartridge to fall therethrough adjacent to their rear end, means for supplying a cartridge at a time to the guide tracks, means for moving the cartridges rearward on the guide tracks one at a time to the enlarged portion of the tracks, a cartridge delivery chute arranged in rear of the cylinder for position in registration with one of the chambers thereof when the cylinder is stationary for receiving a cartridge dropped from the guide tracks, means including a plunger for moving the cartridges one at a time in the delivery tube to a chamber of the cylinder, means for preventing the delivery of more than one cartridge at a time to the delivery tube, and means for turning the cartridges as the same fall from the tracks in a vertical plane to a horizontal plane.
- 25 12. A machine gun comprising a barrel, a cylinder rotatable in rear of the barrel having a plurality of chambers therein, means for rotating the cylinder in a step by step movement for successively bringing a chamber into registration with the barrel, a cartridge feeding mechanism for delivering one cartridge at a time to a chamber of the cylinder including a horizontally disposed delivery tube arranged in rear of the cylinder, a plunger in the delivery tube for moving the cartridges forward one at a time, and a pair of guide tracks for holding cartridges in a suspended position, means for delivering cartridges one at a time to the track, means reciprocatively mounted above the tracks for feeding the cartridges rearward, the tracks being enlarged at their end to permit a cartridge to fall therethrough, a swinging stop arranged in the path of the cartridges for preventing the delivery of more than one cartridge at a time to the enlarged portion of the track, means for positively forcing a cartridge through the enlarged portion of the track, said enlarged portion of the track being located directly above the delivery tube, and means for preventing the delivery of more than one cartridge at a time to the delivery tube.
- 30 13. A machine gun comprising a barrel, a cylinder rotatable in rear of the barrel having a plurality of chambers therein, means for rotating the cylinder in a step by step movement for successively bringing a chamber into registration with the barrel, a cartridge feeding mechanism for delivering one cartridge at a time to a chamber of the cylinder including a horizontally disposed delivery tube arranged in rear of the cylinder, a plunger in the delivery tube for moving the cartridges forward one at a time, and a pair of guide tracks for holding cartridges in a suspended position, means for delivering cartridges one at a time to the track, means reciprocatively mounted above the tracks for feeding the cartridges rearward, the tracks being enlarged at their end to permit a cartridge to fall therethrough, a swinging stop arranged in the path of the cartridges for preventing the delivery of more than one cartridge at a time to the enlarged portion of the track, means for positively forcing a cartridge through the enlarged portion of the track, said enlarged portion of the track being located directly above the delivery tube, and means for preventing the delivery of more than one cartridge at a time to the delivery tube.
- 35 14. A machine gun comprising a barrel, a cylinder rotatable in rear of the barrel having a plurality of chambers therein, means for rotating the cylinder in a step by step movement for successively bringing a chamber into registration with the barrel, a cartridge feeding mechanism for delivering one cartridge at a time to a chamber of the cylinder including a horizontally disposed delivery tube arranged in rear of the cylinder, a plunger in the delivery tube for moving the cartridges forward one at a time, and a pair of guide tracks for holding cartridges in a suspended position, means for delivering cartridges one at a time to the track, means reciprocatively mounted above the tracks for feeding the cartridges rearward, the tracks being enlarged at their end to permit a cartridge to fall therethrough, a swinging stop arranged in the path of the cartridges for preventing the delivery of more than one cartridge at a time to the enlarged portion of the track, means for positively forcing a cartridge through the enlarged portion of the track, said enlarged portion of the track being located directly above the delivery tube, and means for preventing the delivery of more than one cartridge at a time to the delivery tube.
- 40 15. A machine gun comprising a barrel, a cylinder rotatable in rear of the barrel having a plurality of chambers therein, means for rotating the cylinder for successively bringing a chamber in registration with the barrel.

barrel, means for feeding cartridges to a chamber of the barrel including a pair of guide tracks for holding the cartridge in a suspended position, the tracks being enlarged at their rear ends to permit a cartridge to fall therethrough, a horizontally disposed delivery tube arranged directly below the enlarged portions of the tracks arranged in rear of the cylinder for delivering cartridges to a chamber thereof, a plunger rod for delivering cartridges from the delivery tube to a chamber of the gun, means for delivering cartridges one at a time to the guide track including a supply hopper and a control hopper, a delivery tube extending from the supply hopper into the control hopper having its lower end open, a gate hingedly mounted in the control hopper and movable toward and away from the open end of the delivery chute, a pair of jaws arranged in the control hopper directly below the gate and above the guide tracks, one of said jaws being stationary and the other being hinged intermediate its ends and movable toward and away from the rigid jaw, means operatively connecting the movable jaw with the gate whereby when the jaw is moved away from the rigid jaw the gate will be in a closed position and vice versa, a slide track reciprocatively mounted in the control hopper below the jaws and above the guide tracks having a longitudinal slot therein for receiving the weighted end of a bullet, the slot being enlarged at its rear end to permit a bullet to drop therefrom into the guide tracks, a slide plate secured to the slide track for movement therewith having a cam surface for rocking the movable jaw, means including a slide plate and a depending finger for pushing the cartridges on the guide tracks rearward to the enlarged portion of said guide tracks, a trip arm on the cartridge pusher, a hook on the slide tracks arranged in the path of said arm, and means for reciprocating the cartridge pusher.

16. A gun comprising a barrel, a cylinder rotatably mounted in rear of the barrel having a plurality of chambers therein, means for rotating the cylinder to successively bring the chambers in registration with the barrel, means for feeding cartridges into a chamber of the cylinder including a pair of spaced guide tracks for receiving suspended cartridges, means for delivering cartridges one at a time between the tracks, the tracks being spaced a greater distance apart at their rear ends than at their front ends to permit the dropping of a cartridge therethrough, a delivery tube having its upper rear end open and arranged directly below the greater spaced portion of the tracks and leading toward the cylinder, a reciprocating plunger in the delivery tube for moving the cartridges forward one at a time toward the cylinder, means for pushing the cartridges rear-

ward on the tracks toward the enlarged spaced portion of the tracks, a swinging finger movable between the tracks in front of the greater spaced portion thereof to permit the delivery of a single cartridge at a time therethrough, and means for forcibly pushing a cartridge through the greatest spaced portion of the tracks, including a swinging hammer plate, and means for swinging the hammer plate in proper timed relation to the stop finger.

17. A gun comprising a barrel, a cylinder rotatably mounted in rear of the barrel having a plurality of chambers therein, means for rotating the cylinder to successively bring the chambers in registration with the barrel, means for feeding cartridges into a chamber of the cylinder including a pair of spaced guide tracks for receiving suspended cartridges, means for delivering cartridges one at a time between the tracks, the tracks being spaced a greater distance apart at their rear ends than at their front ends to permit the dropping of a cartridge therethrough, a delivery tube having its upper rear end open and arranged directly below the greater spaced portion of the tracks and leading toward the cylinder, a reciprocating plunger in the delivery tube for moving the cartridges forward one at a time toward the cylinder, means for pushing the cartridges rearward on the tracks toward the enlarged spaced portion of the tracks, a swinging finger movable between the tracks in front of the greater spaced portion thereof to permit the delivery of a single cartridge at a time therethrough, means for forcibly pushing a cartridge through the greatest spaced portion of the tracks, including a swinging hammer plate, means for swinging the hammer plate in proper timed relation to the stop finger, and means for preventing the delivery of more than one cartridge at a time to the delivery tube including a reciprocating finger mounted directly above the open portion of the delivery tube, and means for reciprocating the finger in proper timed relation to the hammer plate.

18. A gun comprising a barrel, a cylinder rotatably mounted in rear of the barrel having a plurality of chambers therein, means for rotating the cylinder to successively bring the chambers in registration with the barrel, means for feeding cartridges into a chamber of the cylinder including a pair of spaced guide tracks for receiving suspended cartridges, means for delivering cartridges one at a time between the tracks, the tracks being spaced a greater distance apart at their rear ends than at their front ends to permit the dropping of a cartridge therethrough, a delivery tube having its upper rear end open and arranged directly below the greater spaced portion of the tracks and leading toward the cylinder, a reciprocating plunger in the de-

- 61 delivery tube for moving the cartridges forward one at a time toward the cylinder, means for pushing the cartridges rearward on the tracks toward the enlarged spaced portion of the tracks, a swinging finger movable between the tracks in front of the greater spaced portion thereof to permit the delivery of a single cartridge at a time therethrough, means for forcibly pushing a cartridge through the greatest spaced portion of the tracks, including a swinging hammer plate, means for swinging the hammer plate in proper timed relation to the stop finger, and means for preventing the delivery of more than one cartridge at a time to the delivery tube, and a feed plunger.

62 19. A gun comprising a barrel, a cylinder rotatably mounted in rear of the barrel having a plurality of chambers therein, means for rotating the cylinder to successively bring the chambers in registration with the barrel, means for feeding cartridges into a chamber of the cylinder including a pair of spaced guide tracks for receiving suspended cartridges, means for delivering cartridges one at a time between the tracks, the tracks being spaced a greater distance apart at their rear ends than at their front ends to permit the dropping of a cartridge therethrough, a delivery tube having its upper rear end open and arranged directly below the greater spaced portion of the tracks and leading toward the cylinder, a reciprocating plunger in the delivery tube for moving the cartridges forward one at a time toward the cylinder, means for pushing the cartridges rearward on the tracks toward the enlarged spaced portion of the tracks, a swinging finger movable between the tracks in front of the greater spaced portion thereof to permit the delivery of a single cartridge at a time therethrough, means for forcibly pushing a cartridge through the greatest spaced portion of the tracks, including a swinging hammer plate, means for swinging the hammer plate in proper timed relation to the stop finger, means for preventing the delivery of more than one cartridge at a time to the delivery tube including a reciprocating finger mounted directly above the open portion of the delivery tube, means for reciprocating the finger in proper timed relation to the hammer plate, and means for turning the cartridges to a proper horizontal position during the movement thereof from the guide tracks to the delivery tube including an inclined stop plate and a reciprocating pusher plate for moving the base ends of the cartridges toward the inclined plate, means for locking the cylinder against rotation during the feeding of the cartridge to a chamber thereof, and means for reciprocating the cartridge pusher including a pivoted hook connected therewith, a swinging operating lever mounted in the path of the hook, and means for actuating the lever.

63 20. A gun comprising a barrel, a cylinder rotatable in rear of the barrel having a plurality of chambers therein, a cartridge delivery mechanism including a horizontally disposed delivery tube arranged in rear of the cylinder, means for automatically rotating the cylinder in a step by step movement for successively bringing the chambers thereof into registration with the barrel and with the delivery tube, the rear end of the delivery tube having its upper face open, a pair of spaced delivery tracks above the delivery tube for holding the cartridges in a suspended position therebetween, the rear ends of the tracks being spaced a greater distance to provide a cartridge exit directly above the entrance to the delivery tube, means reciprocately mounted above the tracks having a depending finger disposed between the tracks for engaging the suspended cartridges for gradually pushing the cartridges one at a time toward the exit, and means for reciprocating the finger.

64 21. In a machine gun, a barrel, a cylinder rotatable in rear of the barrel having a plurality of chambers therein, a cartridge delivery tube having its upper rear end open and arranged directly below the greater spaced portion of the tracks and leading toward the cylinder, a reciprocating plunger in the delivery tube for moving the cartridges forward one at a time toward the cylinder, means for pushing the cartridges rearward on the tracks toward the enlarged spaced portion of the tracks, a swinging finger movable between the tracks in front of the greater spaced portion thereof to permit the delivery of a single cartridge at a time therethrough, means for forcibly pushing a cartridge through the greatest spaced portion of the tracks, including a swinging hammer plate, means for swinging the hammer plate in proper timed relation to the stop finger, means for preventing the delivery of more than one cartridge at a time to the delivery tube including a reciprocating finger mounted directly above the open portion of the delivery tube, means for reciprocating the finger in proper timed relation to the hammer plate, and means for turning the cartridges to a proper horizontal position during the movement thereof from the guide tracks to the delivery tube including an inclined stop plate and a reciprocating pusher plate for moving the base ends of the cartridges toward the inclined plate, means for locking the cylinder against rotation during the feeding of the cartridge to a chamber thereof, and means for reciprocating the cartridge pusher including a pivoted hook connected therewith, a swinging operating lever mounted in the path of the hook, and means for actuating the lever.

65 22. In a machine gun, a barrel, a cylinder rotatable in rear of the barrel having a plurality of chambers therein, a cartridge delivery tube having its upper rear end open and arranged directly below the greater spaced portion of the tracks and leading toward the cylinder, a reciprocating plunger in the delivery tube for moving the cartridges forward one at a time toward the cylinder, means for pushing the cartridges rearward on the tracks toward the enlarged spaced portion of the tracks, a swinging finger movable between the tracks in front of the greater spaced portion thereof to permit the delivery of a single cartridge at a time therethrough, means for forcibly pushing a cartridge through the greatest spaced portion of the tracks, including a swinging hammer plate, means for swinging the hammer plate in proper timed relation to the stop finger, means for preventing the delivery of more than one cartridge at a time to the delivery tube including a reciprocating finger mounted directly above the open portion of the delivery tube, means for reciprocating the finger in proper timed relation to the hammer plate, and means for turning the cartridges to a proper horizontal position during the movement thereof from the guide tracks to the delivery tube including an inclined stop plate and a reciprocating pusher plate for moving the base ends of the cartridges toward the inclined plate, means for locking the cylinder against rotation during the feeding of the cartridge to a chamber thereof, and means for reciprocating the cartridge pusher including a pivoted hook connected therewith, a swinging operating lever mounted in the path of the hook, and means for actuating the lever.

ery mechanism including a horizontally disposed delivery tube arranged in rear of the cylinder, means for automatically rotating the cylinder in a step by step movement for successively bringing the chambers thereof into registration with the barrel and with the delivery tube for holding the cartridges in a suspended position therebetween, the rear ends of the tracks being spaced a greater distance to provide a cartridge exit directly above the entrance to the delivery tube, means reciprocatively mounted above the tracks having a depending finger disposed between the tracks for engaging the suspended cartridges for gradually pushing the cartridges one at a time toward the exit, means for reciprocating the finger, and a stop finger disposed in the path of the cartridges and arranged in front of the cartridge exit, means hingedly connecting the stop finger for swinging movement, whereby the same can be raised or lowered, and means for automatically raising and lowering said stop finger.

23. In a machine gun, a barrel, a cylinder rotatable in rear of the barrel having a plurality of chambers therein, a cartridge delivery mechanism including a horizontally disposed delivery tube arranged in rear of the cylinder, means for automatically rotating the cylinder in a step by step movement for successively bringing the chambers thereof into registration with the barrel and with the delivery tube for holding the cartridges in a suspended position therebetween, the rear ends of the tracks being spaced a greater distance to provide a cartridge exit directly above the entrance to the delivery tube, means reciprocatively mounted above the tracks having a depending finger disposed between the tracks for engaging the suspended cartridges for gradually pushing the cartridges one at a time toward the exit, means for reciprocating the finger, a stop finger disposed in the path of the cartridges and arranged in front of the cartridge exit, means hingedly connecting the stop finger for swinging movement, whereby the same can be raised or lowered, means for automatically raising and lowering said stop finger, and means for positively forcing the cartridges through the exit including a hinged hammer plate arranged directly above the exit, a slide link hingedly connected to the hammer plate adjacent to the free end thereof, spring means normally urging the slide plate to a rearward position and the hammer plate to a raised position, and means for reciprocating the slide plate.

24. In a machine gun comprising a barrel, a cylinder rotatable in rear of the barrel, a cartridge feeding mechanism, the cylinder having a plurality of chambers therein, means for automatically turning the cylinder to successively bring the chambers thereof into registration with the barrel and de-

livery tube, the rear end of the delivery tube having its upper face open to receive cartridges therein, means for feeding the cartridges one at a time to the delivery tube, a reciprocating plunger movable in the delivery tube for delivering the cartridges to the front of the delivery tube and into a chamber of the cylinder, a master operating lever rockably mounted intermediate its ends, means for rocking said master operating lever, and means for reciprocating the plunger of the master operating lever.

25. In a machine gun comprising a barrel, a cylinder rotatable in rear of the barrel, a cartridge feeding mechanism, the cylinder having a plurality of chambers therein, means for automatically turning the cylinder to successively bring the chambers thereof into registration with the barrel and delivery tube, the rear end of the delivery tube having its upper face open to receive cartridges therein, means for feeding the cartridges one at a time to the delivery tube, a reciprocating plunger movable in the delivery tube for delivering the cartridges to the front of the operating lever rockably mounted intermediate its ends, means for rocking said master operating lever, means for reciprocating the plunger of the master operating lever, and a reciprocating stop finger arranged above the entrance to the delivery tube for preventing more than one cartridge at a time to be delivered to the tube, and means for reciprocating the finger from the master operating lever.

26. In a machine gun, a barrel, a cylinder rotatable in rear of the barrel having a plurality of chambers therein, a cartridge delivery tube arranged in rear of the barrel, a master operating lever rockably mounted intermediate its ends below the cylinder, means for continuously rocking the master operating lever, means actuated from the master operating lever for turning the cylinder in a step by step movement for successively bringing the chambers thereof into successive registration with the barrel and delivery tube, the rear end of the delivery tube having its upper face provided with an entrance slot, a three armed lever rockably mounted intermediate its arms, means operatively connecting one of said arms to the master operating lever, a pair of spaced guide tracks for holding cartridges in a suspended position therebetween, means for delivering cartridges one at a time between the tracks, the rear ends of the tracks being spaced a greater distance apart to provide a cartridge exit directly above the entrance slot of the delivery tube, a reciprocating slide plate for urging the cartridges rearwardly of the track toward the exit, a pivoted hook carried by the forward end of the slide plate, a swinging lever rockably mounted intermediate its ends, a link connecting the

- lower end of the swinging lever to the three arm lever below its pivot, the hook being arranged in the path of the upper end of the swinging lever, a delivery plunger rod reciprocatively mounted in the delivery tube, means for reciprocating the rod from the three armed lever, a slide control member mounted directly above the entrance of the delivery chute for preventing the delivery of more than one cartridge at a time thereto, means for reciprocating the finger on the three arm lever, a swinging stop finger movable between the tracks directly above the exit for controlling the flow of cartridges to the exit, means for swinging the finger from the three arm lever, means for positively forcing the cartridges through the exit one at a time, and means for operating the cartridge forcing means from the three armed lever.
27. In a gun of the class described, a barrel, a cylinder rotatable in rear of the barrel provided with a plurality of chambers, means for turning the cylinder in a step by step movement to successively bring the chambers thereof into registration with the barrel, said means including a master operating lever rockably mounted intermediate its ends, means for continuously rocking the master lever, a lift lever pivotally connected to the master operating lever extending toward the cylinder and having a laterally projecting dog for engaging the walls of the chambers of the cylinder, means for normally holding the dog resiliently toward the cylinder, and a guard and guide finger formed on the lift lever for engaging the outer face of the cylinder.
28. In a machine gun, a barrel, a cylinder rotatable in rear of the barrel having a plurality of chambers therein, means for turning the cylinder to successively bring the chambers thereof into registration with the barrel, means for feeding cartridges to the chambers of the gun, means for firing the cartridges in the chamber which is in registration with the barrel including a reciprocating firing pin, spring means normally holding the firing pin in rear of the cartridge, a reciprocating hammer mounted in rear of the firing pin, having a cross pin, a firing lever rockably mounted intermediate its ends, having its upper end provided with a yoke for engaging the cross pin, a heavy contractile coil spring engaging the lower end of the firing lever below its pivot for normally urging the upper end thereof in engagement with the cross pin, and the hammer toward the firing pin, a laterally extending arm formed on the rear end of the hammer, a swinging lever, a latch pivoted on the upper end of the swinging lever, spring means normally urging the latch into engagement with the arm of the hammer for normally holding the same against movement under the influence of the spring of the firing lever, means for swinging the latch on the swinging lever for releasing the firing hammer, and means for oscillating the lever for moving the latch over the lateral arm, and for returning the hammer to its normal cocked position.
29. In a machine gun, a barrel, a cylinder rotatable in rear of the barrel, means for turning the cylinder in a step by step movement to successively bring the chambers thereof into registration with the barrel, a firing mechanism located in rear of the cylinder, means for ejecting the exploded shells from the gun comprising a reciprocating ejector rod movable toward and away from the cylinder of the gun and into and out of a chamber of the cylinder, means for reciprocating the rod including a lever rockably mounted intermediate its ends, a pin and slot connection between the upper end of the lever and the ejecting rod, a pair of rearwardly extending hooks pivotally connected to the lever on opposite sides of its pivot, a guide for the hooks, a reciprocating rod having a laterally extending lug, means for continuously reciprocating the rod, the hook being arranged in the path of the lug, and means for automatically lifting one of the hooks from out of the path of the lug at a predetermined time.
30. In a machine gun, a barrel, a cylinder rotatable in rear of the barrel, means for turning the cylinder in a step by step movement to successively bring the chambers thereof into registration with the barrel, a firing mechanism located in rear of the cylinder, means for ejecting the exploded shells from the gun comprising a reciprocating ejector rod movable toward and away from the cylinder of the gun and into and out of a chamber of the cylinder, means for reciprocating the rod including a lever rockably mounted intermediate its ends, a pin and slot connection between the upper end of the lever and the ejecting rod, a pair of rearwardly extending hooks pivotally connected to the lever on opposite sides of its pivot, a guide for the hooks, a reciprocating rod having a laterally extending lug, means for continuously reciprocating the rod, the hook being arranged in the path of the lug, means for automatically lifting one of the hooks from out of the path of the lug at a predetermined time, and means for receiving the exploded shells from the cylinder.
31. A machine gun comprising a barrel, a cylinder rotatable in rear of the barrel provided with a plurality of chambers, means for turning the cylinder in a step by step movement for successively bringing the chambers thereof into registration with the barrel, a firing mechanism arranged in rear of the cylinder, means for feeding cartridges to the chambers of the gun, means for ejecting exploded shells from the cylinder, and means for locking the cylinder positively against

rotation during the firing, loading and ejecting operation, including a reciprocating lock pin movable into and out of a chamber of the gun, a light spring normally urging the pin into a chamber of the gun, a guide rod, a guide eye formed on the rear end of the lock pin slideable on the guide rod, a pivoted lever, means for swinging the lever continuously, an upwardly extending arm formed on the lever adjacent to its pivot, a forwardly extending hook pivoted to the upper end of the arm normally overhanging the guide eye, a relatively heavy coil spring engaging the hook for holding the same in engagement with the guide eye, a guide pin arranged below the swinging hook, the swinging hook having a cam surface for engaging the pin, whereby upon swinging movement of the lever, the hook will be moved back and forth to actuate the lock pin.

32. A machine gun comprising a barrel, a cylinder rotatable in rear of the barrel, having a plurality of chambers therein, means for turning the cylinder in a step by step movement for successively bringing the chambers thereof into registration with the barrel, a firing mechanism located in rear of the cylinder, means for successively feeding cartridges into the chambers of the cylinder, means for ejecting exploded shells from the chambers, and means for cooling the gun including a water jacket surrounding the barrel, having a projecting portion overhanging the cylinder, means including a pump for circulating water to the jacket, the overhanging portion of the chamber being provided with drip openings for delivering water over the openings, a pan for receiving the drip water, and means for returning the drip water to the means for circulating the water.

In testimony whereof I affix my signature.
